UNITED STATES PATENT OFFICE.

ISAAC H. MILLIKEN, OF ASPINWALL, PENNSYLVANIA, ASSIGNOR TO THE McCONWAY & TORLEY COMPANY, OF PITTSBURGH, PENNSYLVANIA, A CORPORATION OF PENNSYLVANIA.

COUPLING AND YOKE CONNECTION.

1,404,878.

Specification of Letters Patent. Patented Jan. 31, 1922.

Application filed August 6, 1920. Serial No. 401,607.

To all whom it may concern:

Be it known that I, ISAAC H. MILLIKEN, a citizen of the United States, residing at Aspinwall, in the county of Allegheny and 5 State of Pennsylvania, have invented certain new and useful Improvements in Coupling and Yoke Connections; and I do hereby declare the following to be a full, clear, and exact description of the invention, such 10 as will enable others skilled in the art to which it appertains to make and use the same.

My invention relates to a coupler and yoke connection for the draft rigging of railway 15 cars whereby couplers of the type commonly applied to freight cars may be made available for use in equipping passenger cars where it is desirable that the coupler shall be capable of swinging laterally with respect to the car body when the train passes 20 around a curve. Car couplers designed for application to freight cars are usually incapable of any substantial horizontal swinging movement with respect to the yoke, being 25 commonly rigidly connected to the latter or else capable only of longitudinal sliding movement with respect thereto. My invention provides means for pivotally connecting such couplers to draft yokes in a 30 strong, simple, durable and efficient manner permitting them to execute extended lateral swinging movements.

The primary features of the invention, generally stated, consist in providing a 35 coupler stem extension which is adapted to be pivotally connected to a draft yoke and which has a forwardly opening socket for receiving the rear end of the stem of the coupler, the latter having a transversely extending horizontal slot adjacent its rear end 40 for the reception of a key whose outer ends project into key receiving recesses formed on the interior of the said socket. The key constitutes means for transmitting draft 45 strains from the coupler stem to the stem extension member and for preventing relative movement of these parts while the coupler is executing a buffing movement. The socket at the forward end of the coupler stem extension is of a character enabling the rear 50 end of the coupler stem to be inserted after the connecting key has been positioned in the slot in the coupler stem, and said socket is so designed that after the coupler stem has been inserted and elevated to assembled po-

sition the ends of the key cooperate with shoulders on the stem extension within the socket to prevent withdrawal of the coupler and to transmit to the coupler stem extension shocks incident to service. Efficient 60 resistance to great buffing shocks is effected by providing the coupler stem extension with a transversely extending web forming a seat for the rear end of the coupler stem, and by bracing said web by means of the oppositely 65 disposed spaced walls and a longitudinally extending web between said walls, said last named web being integrally united to the transversely extending web in alinement with the coupler stem and the said spaced 70 walls being united to the transversely extending web adjacent the outer edges of the rear end of the coupler stem. Buffing shocks which may be communicated to the coupler 75 stem extension through the connecting key are efficiently resisted by providing the opposite sides of the coupler stem extension at points adjacent the rear edge of the key with braces extending inwardly from the outer 80 ends of said key.

In the drawings illustrating the invention, the scope whereof is pointed out in the claims,—

Figure 1 is a plan view of a coupler and yoke connection embodying the invention, 85 the coupler head, a portion of the coupler stem extension, which may be of any desired length, and a portion of the draft yoke being omitted.

Fig. 2 is a side elevation of the construction.

Fig. 3 is an end elevation of the devices shown in Fig. 1.

Fig. 4 is a detail vertical section on the line 4—4, Fig. 1.

Fig. 5 is a detail sectional view on the line 5—5, Fig. 1.

Fig. 6 is a detail section on the line 6—6, Fig. 2.

Fig. 7 is a transverse section on the line 100 7—7, Fig. 2.

Fig. 8 is a sectional view corresponding to Fig. 5, but illustrating a modification of the invention.

Fig. 9 is a perspective view of the modified form of key shown in Fig. 8.

In the drawings 1 indicates the stem of a car coupler, and 2 is a coupler stem extension through the intermediacy of which the coupler is pivotally connected to the 110

draft yoke 3. For the purpose of forming the pivotal connection of the draft yoke with the coupler stem extension the latter may conveniently be provided at its rear end with a plurality of vertically spaced pivot lugs 4, 5 and 6, respectively, between which the perforated forward ends 7 of the yoke are received. A downwardly removable pivot pin 8 passes through the apertures in the ends of 10 the yoke and in the pivot lugs of the coupler stem extension 2, thus connecting these parts.

The stem 1 of the car coupler is provided adjacent its rear end with a transversely extending horizontal slot 9 which receives a correspondingly shaped key 11. This key partakes of the draft and buffing movements of the coupler stem.

The coupler stem extension is provided at 20 its forward end with a socket 12 which receives the rear end of the coupler stem, and is formed with oppositely disposed key receiving recesses 13 of greater height at their rear ends than at their forward ends and 25 which terminate in advance of the inner end of the socket. These key recesses 13 thus afford front and rear shoulders 14 and 15, respectively, which engage and vertically overlap the corresponding edges of the key 30 11 at its outer end. In order to allow the key 11 when mounted in the slot at the rear end of the coupler stem 1 to be brought to assembled position, the socket 12 is made of greater height than the rear end of the 35 coupler stem, thus permitting the latter to be inserted in the socket at an elevation allowing the key to pass beneath the forward shoulders 14. The coupler stem is subsequently elevated in the socket sufficiently 40 to position the key in horizontal alignment with the shoulders 14.

The coupler stem 1 is preferably maintained in elevated or assembled position within the socket of the coupler stem extension 2 by means of a plurality of fillers 16 and 17, respectively, which are interposed between the coupler stem and the floor of the coupler stem extension. These filler members are so designed as to afford an 45 extended bearing for the rear end of the coupler stem, thus minimizing the tendency of the coupler to droop. For convenience of assembly and removal these fillers, which are preferably connected, are positioned 50 and withdrawn through an opening 18 which pierces the lower wall of the socket portion of the coupler stem extension so as to afford communication with said socket. The opening 18 in the lower wall of the 60 socket 12 is also advantageous in that it provides means for readily removing the core employed for forming the socket and permits convenient access to the interior of the socket for the purpose of removing any 65 inequalities in the casting which might in-

terfere with the passage of the key 11 or its proper engagement with the shoulders 14 and 15. The forward filler 16 is preferably provided at its rear end on its under side with a pair of spaced perforated lugs 70 19, and the rear filler 17 is preferably provided with a forwardly extending perforated arm 20 which is adapted to extend between the said lugs 19. A cotter 21' which passes through the perforated lugs 19 and 75 arm 20 serves to connect the fillers and retain them in assembled positions.

The rear end of the socket 12 in the coupler stem extension 2 is closed by a transverse web 21 affording a seat or bearing 80 for the rear end of the coupler stem 1. Rearwardly of said transversely extending web the stem extension 2 is preferably made of hollow cross section so as to afford spaced side walls 22 and spaced top and bottom 85 walls 23 which are integrally united to the transversely extending web 21 in substantial alignment with the edges of the rear end of the coupler stem. Within the hollow portion of the coupler stem extension formed by the 90 oppositely disposed walls 22 and 23 is preferably formed a longitudinally extending web 24 which is integrally united to the transverse web 21 in alignment with the coupler stem 1. The web 24 which is united throughout its length to the spaced walls 23, being in the direct line of buffing strain imparted to the coupler stem extension 2 by the coupler stem 1, serves to reinforce the transversely extending web 21 against buffing shocks 100 in a very efficient manner.

The coupler stem extension 2 is preferably fashioned upon opposite sides adjacent the rear edge of the key 11 with external bracing ribs 25 which are in horizontal 105 alignment with said key and extend inwardly from the outer ends thereof so as to support the key engaging shoulders 15 against buffing strains imparted thereto.

The modification seen in Figs. 8 and 9 110 shows a construction employing a slightly different form of key for connecting the coupler stem 1 to the coupler stem extension 2. In the modified construction the key 26 is formed adjacent its 115 outer ends with flat edge faces 27 which therefore, afford a somewhat greater bearing area against the shoulders 14' and 15' of the coupler stem extension. The central portion 28 of the key 26 lying within the 120 lines of the coupler stem 1 has rounded edges as in the case of the key 11 heretofore described.

I claim:

1. In a device of the character indicated, 125 the combination with a coupler stem having a transversely extending horizontal slot adjacent its rear end, of a coupler stem extension adapted to be pivotally connected to a draft yoke and having a forwardly 130

- opening socket adapted to receive the rear end of said coupler stem, said socket being of greater height than the rear end of said coupler stem and being formed with oppositely disposed key receiving recesses which are of greater height at their rear ends than at their forward ends, a key extending through the slot of said coupler stem and having its ends projecting into said key receiving recesses, and a plurality of filler members interposed between said coupler stem extension and coupler stem for supporting the latter in elevated position in said socket, said coupler stem extension being provided with an aperture extending through its lower side and affording communication with said socket to permit said filler members to be inserted and removed, and said key constituting means for transmitting draft strains from said coupler stem to said coupler stem extension and for preventing relative movement of said coupler stem and coupler stem extension during buffing movement of said coupler stem.
2. In a device of the character indicated, the combination with a coupler stem having a transversely extending horizontal slot adjacent its rear end, of a coupler stem extension adapted to be pivotally connected to a draft yoke and having a forwardly opening socket adapted to receive the rear end of said coupler stem, a key extending through the slot of said coupler stem and constituting means for transmitting draft forces from said coupler stem to said coupler stem extension and for preventing rearward movement of said coupler stem with respect to said coupler stem extension during a buffing movement of said coupler stem, and means for retaining said coupler stem in elevated position in said socket of the coupler stem extension, the surfaces of said coupler stem within said socket being free from external shoulders or projections, and said socket being of greater height than the rear end of said coupler stem and being formed with oppositely disposed recesses affording shoulders adapted to engage the opposite edges of said key.
3. In a device of the character indicated, the combination with a coupler stem having a transversely extending horizontal slot adjacent its rear end, of a coupler stem extension adapted to be connected to a draft yoke and having a forwardly opening socket adapted to receive the rear end of said coupler stem, said socket being of greater height than the rear end of said coupler stem and having a transversely extending rear wall affording a seat for the rear end of said coupler and being formed with oppositely disposed key receiving recesses which are of greater height at their rear ends than at their forward ends, a key extending through the slot of said coupler stem and having its ends projecting into said key receiving recesses, and means for retaining said coupler stem in elevated position in said socket of the coupler stem extension.
4. In a device of the character indicated, the combination with a coupler stem, of a coupler stem extension adapted to be connected to a draft yoke and having a forwardly opening socket for receiving the rear end of said coupler stem, said socket being of greater height than the rear end of said coupler stem and having a transversely extending rear wall against which the rear end of said coupler stem is adapted to bear and being formed with oppositely disposed recesses which are of greater height at their rear ends than at their forward ends, key means carried by said coupler stem and projecting into said recesses, and means for retaining said coupler stem in elevated position in said socket, said retaining means comprising a plurality of downwardly removable detachably connected filler members interposed between said coupler stem extension and coupler stem, and said coupler stem extension being provided with a downwardly opening aperture communicating with said socket and permitting said filler members to be inserted and removed.
5. In a device of the character indicated, the combination with a coupler stem having a transversely extending horizontal slot adjacent its rear end, of a coupler stem extension adapted to be connected to a draft yoke and having a forwardly opening socket adapted to receive the rear end of said coupler stem, said socket being of greater height than the rear end of said coupler stem and being formed with key receiving recesses which are of greater height at their rear ends than at their forward ends and which terminate in advance of the inner end of said socket, a key extending through the slot of said coupler stem and projecting into said key receiving recesses, and means for retaining said coupler stem in elevated position in said socket, said coupler stem extension being integrally provided upon opposite sides adjacent the rear edge of said key with braces extending inwardly from the outer ends of said key.

In testimony whereof I affix my signature.
ISAAC H. MILLIKEN.
